UNITED STATES PATENT OFFICE.

CHARLES H. FRENCH, OF CANTON, MASSACHUSETTS, ASSIGNOR TO FRENCH & WARD, OF NEW YORK, N. Y., A FIRM.

DESIGN FOR EIDER-DOWN CLOTH.

No. 38,045.

Specification for Design.

Patented May 29, 1906.

Application filed March 7, 1906. Serial No. 304,799. Term of patent 14 years.

To all whom it may concern:

Be it known that I, CHARLES H. FRENCH, a citizen of the United States, and a resident of Canton, in the county of Norfolk and State of Massachusetts, have invented a new, original, and ornamental Design for Eider-Down Cloth, reference being had to the accompanying drawings, in which the figure is a perspective view of a piece of eider-down cloth, showing my design.

I claim—

The ornamental design for eider - down cloth as shown .

CHARLES H. FRENCH.
